H. DOHERTY, JR

STOP MOTION

Filed Feb. 21, 1927

INVENTOR
Henry Doherty Jr.,
BY
John Seward,
ATTORNEY.

W. M. Mell.

WITNESS

Patented Oct. 25, 1927.

UNITED STATES PATENT OFFICE.

HENRY DOHERTY, JR., OF CLIFTON, NEW JERSEY.

STOP MOTION.

Application filed February 21, 1927. Serial No. 169,828.

It is known that in weaving and also in warping two or more warp threads will occasionally become bound together so effectively, as by their fibres intersnarling, that 5 where a lease is formed in the warp the connection, or "sticker" as it is sometimes called, thus established will not break down before one or more of the threads involved itself breaks and the unusual strain has produced 10 a blemish in the goods or some other fault. For detecting such "stickers" careful weavers sometimes resort to a makeshift detecting means consisting of a cord which is anchored at one end, extends through the shed 15 formed by the lease-rods and has a light weight at its other end, undue upward movement of the weight indicating that a sticker has caught the cord, flexing it forward. The object of this invention is to provide 20 means for detecting stickers in an advancing warp which shall be more reliable in its operation than the makeshift means referred to and which may be used to actuate mechanism for stopping the loom or other machine.

In the drawing,

Fig. 1 is a vertical front to rear sectional view showing my invention in place on a loom, the principal elements of which concerned in the support and advance of the warp are shown;

Fig. 2 is a plan of the invention and the rear part of so much of the loom as appears in Fig. 1;

Fig. 3 is a side elevation on a larger scale of what appears in Fig. 2, with parts 13 and 15 removed; and

Fig. 4 shows a sticker acting on the flexible part 8.

In the drawing, A is the sheet of warp and woven fabric extending from the warp-beam 1, subject to some braking means 2, over the whip-roll 3 and breast-beam 4, to the take-up means 4^a. 5 is the batten or lay, 40 6 the harness for forming sheds A' in the warp, and 7 the pair of lease-rods for maintaining a cross and consequently what might be termed lease-sheds in the warp.

A cord or other flexible elongated device 50 8 extends through one of the sheds B', as the rear one and back of the rear lease-rod. This cord is not allowed to ride on the lower sheet of the warp but is supported clear of 55 preferably both sheets, as by two pulleys 9 around which it extends. These pulleys 9 are journaled on vertical axes in arms 10

that are adjustable forward and back in the bent-off ends of other arms 11 secured by set-screws 12 in brackets 13 upstanding from the loom-frame 14. The arms 11 carry 60 other brackets 15; these brackets support the ends of the lease-rods 7 and they also carry, suitably insulated therefrom and arranged above the lease-rods, the bars 16, 16' forming here the terminals of an electric circuit 17 65 containing the source of energy 18 and an electro-magnet 19 whose armature is here assumed to be the controller lever 20 of the loom. On passing around the pulleys 9 the ends of the device 8 extend forward under 70 the rear lease-rods 7 and upward, being attached to the detectors, each of which is a metallic spring bridging the two terminals 16, 16' and secured to one of them and normally spaced from the other.

When a sticker occurs, as at B in Figs. 2 and 4, it draws forward the device 8, which of course results in a pull on one or both of the members 21 and moves the same to detecting position, which in the present case would be where the detector contacts with the bar 16' and so closes the circuit, 75 stopping the loom.

There is a distinct advantage in providing 80 as an anchorage at each end of the device 8 a detector, as 21, in that the mechanism operates with certainty wherever a sticker appears in the entire width of the warp. It is also of advantage that each detector 85 be normally held, as is the case in the illustrated construction, in a given position, 90 since thereby not only the device 8 is returned from flexed to normal position when released by the sticker but device 8 is kept 95 from working lengthwise in one direction or the other as it would do if it were simply kept taut by two weights, one at each end.

Having thus fully described my invention 100 what I claim and desire to secure by Letters Patent is:

1. In combination, means to support and 105 advance a group of warp threads having a shed therein, a detector elastically held in a given position but movable to detecting position, and means to transmit such movement to said detector including a flexible elongated device attached to said detector, anchored at a point removed therefrom and between said detector and point extending through the shed.

2. In combination, means to support and 110 advance a group of warp threads having a

shed therein, a pair of detectors each normally held in a given position but movable to detecting position, and means to transmit such movement to one of said detectors 5 including a flexible elongated device attached to both detectors and between them extending through said shed.

3. In combination, means to support and advance a group of warp threads having a 10 shed therein, a pair of detectors each spring-held in a given position but movable to detecting position, and means to transmit such movement to one of said detectors including a flexible elongated device attached to both 15 detectors and between them extending through said shed.

4. In combination, means to support and advance a group of warp threads having a 20 shed therein, a detector normally held in a given position but movable to detecting position, means to transmit such movement to said detector including a flexible elongated device attached to said detector, anchored at a point removed therefrom and between 25 said detector and point extending through the shed, and means to support said device clear of the threads of such shed.

5. In combination, means to support and advance a group of warp threads having a

shed therein, electro-magnetic means to be 30 actuated including a circuit having spaced terminals forming a break therein, a circuit-closing member movable from one to the other of two positions into and out of circuit-closing relation to said terminals and 35 normally held in one of them, and means to move said member to the other position including a flexible elongated device attached to said member, anchored at a point removed therefrom and between said detector and point extending through the 40 shed.

6. In combination, means to support and advance a group of warp threads having a 45 shed therein, electro-magnetic means to be actuated including a circuit having spaced 50 terminals forming a break therein, circuit-closing members each movable from one to the other of two positions into and out of circuit-closing relation to said terminals and normally held in one of them, and means to move each of said members to the other position including a flexible elongated device 55 attached to said members and between them extending through the shed.

In testimony whereof I affix my signature.

HENRY DOHERTY, JR.
